Fig. 3

Fig. 4

Fig. 5

Fig. 6

Fig. 7

Fig. 8

FIG. 1 is a front elevational view of a combined bathtub spout, showerhead and control apparatus embodying my new design;

FIG. 2 is a side elevational view thereof;

FIG. 3 is a fragmentary front elevational view of the top portion thereof;

FIG. 4 is a fragmentary front elevational view of the bottom portion thereof;

FIG. 5 is a fragmentary side elevational view of the top portion thereof;

FIG. 6 is a fragmentary side elevational view of the bottom portion thereof;

FIG. 7 is a fragmentary perspective view of the top portion thereof; and

FIG. 8 is a fragmentary perspective view of the bottom portion thereof.

I claim:

The ornamental design for a combined bathtub spout, showerhead and control apparatus, substantially as shown.
